UNITED STATES PATENT OFFICE.

JOHN F. IVARSON, OF BOSTON, MASSACHUSETTS.

DEVICE FOR CUTTING THREADS AND OTHER LATHE-WORK.

1,029,014.

Specification of Letters Patent. Patented June 11, 1912.

Application filed September 10, 1909. Serial No. 517,140.

To all whom it may concern:

Be it known that I, JOHN F. IVARSON, a citizen of the United States, residing at Boston, in the county of Suffolk and State 5 of Massachusetts, have invented new and useful Improvements in Devices for Cutting Threads and other Lathe-Work, of which the following is a specification.

This invention relates to thread cutting devices. More particularly, it relates to improvements in the art of cutting a screw thread on bolts, etc., involving improvements in the manner of mounting and feeding tools in a lathe.

To this end it comprises an improved tool for V-threads, and improvements in the means for mounting, adjusting and feeding the tool, whereby the cutting is done by a single edge of the tool, the tool is positively controlled at all times and may be adjusted while the lathe is running, and the other improvements incidental to the apparatus hereinafter described are attained.

According to the invention, the tool 25 feeds into the work along one face of the thread, cutting the other face of the thread with its single main cutting edge, which runs in a straight line across the entire end of the tool. This gives easy and free cutting; eliminates trouble heretofore arising from the point of old style tools wedging into the work and leaves a smooth-cut surface. The shape of the thread being determined by the angle of feed, which is set 35 and fixed by means provided for that purpose, entirely eliminates the use of a thread gage in getting the tool at proper angle as heretofore and reduces the possibility of error by careless work.

The means provided by the invention enables raising or lowering the tool without disturbing its adjustment otherwise in the thread which it is cutting.

The invention also enables both ends of 45 the tool to be used for cutting blades and is adapted to hold tools of slightly varying size in a position which is automatically made correct; and provides means by which the sliding friction or resistance of the tool 50 in feeding can be adjusted.

The feed of the tool into the thread is independent of the cross slide of the lathe heretofore customarily used.

An embodiment of the invention is illustrated in the accompanying drawing, in which--

Figure 1 is a plan in section on the line 1--1 of Fig. 2; Fig. 2 is a side elevation; Fig. 3 is an elevation of a detail, enlarged, in section on the line 3--3 of Fig. 2; and Fig. 4 is an elevation of a detail. Fig. 5 is a fragmentary elevation of the supporting part 41 and groove 40, as viewed at the part of Fig. 1 opposite which Fig. 5 is placed. Fig. 6 is a fragmentary elevation looking in the opposite direction in section on line 6--6 of Fig. 1 with the screw 25 in place.

Referring to the drawings 10 represents the tail stock of a lathe and 11 a piece of work in the lathe, these being arranged as 70 heretofore customary, and the axis of the lathe being on the line A indicated in this portion of Fig. 1. The tool is marked 12, the groove in which it rests 13 (Fig. 3). A screw 14 clamps it in a block 15 which feeds 75 to and fro with the tool. The block is controlled by screw 20 which has a journal or bearing 21' in a pedestal 21 rising from the base plate 16. At the end remote from the work the pedestal is pivotally connected 80 to the base, the pivot being marked 22 and being arranged horizontally perpendicular to the axis of screw 20. The pedestal extends toward the work from this pivot, having a slot 23 in which the block 15 slides. 85 At the end of this pedestal nearest the work a vertical hole 24 accommodates a knurled screw 25 whose end 26 rests upon the base 16. In the portion of the pedestal next the work is groove 13 in which the tool 12 rests. 90 The tool, therefore, is supported in the pedestal 21 and is adjustable therein by screw 20; and is adjusted therewith when said pedestal is raised or lowered by turning the screw 25, at which times it swings 95 about its pivot 22. A clamp screw 29 which runs through a slot 30 in a lug 28 rising from the base 16 enables the pedestal 21 to be clamped firmly at whatever elevation is desired. The screw is manipulated by a hand wheel 31 fast thereon. The screw has a groove in its unthreaded shank in which a split ring 34 is seated and fits against a shoulder 33 at the end of a short annular recess in the pedestal 21 surrounding screw 100 20. These parts are assembled by first

pushing the screw 20 into the pedestal so that the groove 32 is fully exposed within slot 23; then putting the split ring 34 or such other device as desired in the groove, 5 and then drawing the screw 20 outward till this ring enters the recess and seats against the shoulder 33. After this the hand wheel 31 is put on and made fast to the shaft of screw 20, thus holding the parts in the position shown.

The base plate 16 is adapted to fit the groove 40 in a slide rest 41 of a lathe in which the tool post of a lathe ordinarily fits. It is understood that in applying the 15 invention any ordinary or suitable means may be employed for causing the slide rest 41, which may be considered as on or comprising the carriage of the lathe, to travel to and fro parallel to the line A which is 20 the axis of the work. As such means are well understood in the art, they are omitted from the drawing for the sake of simplicity and to save complications. For the same reason a portrayal of an entire 25 lathe is omitted, the tail stock 10 being shown to indicate the presence and relative position of any suitable type of lathe, and the piece of work or stock 11 with the axis line A signifying the position of the work 30 and its axis and the axis of the lathe. The base plate 16 is secured in position on this slide rest and thereby is secured in a definite angular relation to the axis of the lathe, viz., parallel thereto, as here represented, in 35 the manner following. It has lugs 17, 18 projecting downward and adapted to engage in the groove of the slide rest customarily found in the tool supporting arrangement 40 of a lathe, this being the groove in which the collar under the tool post of a lathe is ordinarily engaged.

In the drawings the part 41 represents a rest or plate on the carriage of the lathe which is supported and connected by any 45 suitable mechanism so that it moves to and fro in a line parallel with the line A of Fig. 1. The head of bolt 36' fits loosely in this groove, its shaft projecting upward, as seen in the fragmentary elevation at the right of Fig. 1, and when the plate 16 is in place, the bolt projects up through the hole 36 therein and the plate is clamped down tight by means of this bolt in the well known manner. The groove 40 in the plate 41, 50 which groove is seen in elevation at the right of Fig. 1 and is seen mostly in dotted lines in Fig. 1, runs parallel to the line A. The plate 16, therefore, when the apparatus is in use, is clamped rigidly to the plate 41 by bolt 36', with its lugs 17, 18, pressed 55 against one side of the groove as represented in the drawing.

For some purposes it may be desirable or possible to have the fixed angular relation between this groove and the axis

of the work something other than one of parallelism and therefore the patent is not to be limited merely to parallelism, although the angular relation which, in a mathematical sense is expressed by the term parallel, is that which is preferred for ordinary purposes. When pressed against the shoulder formed by either side of this groove, the lugs 17, 18 are consequently in a line parallel to the axis of the lathe 70 which in Fig. 1 is represented by line A. The cross feed, being at right angles to the axis of the lathe, as customary, works in the direction of the line B. The groove 13 and screw 20 are set on the upper side of plate 16 at an angle with respect to the lugs 17, 18, on the under side, corresponding to the angle with respect to the axis of the lathe desired for one face of the thread. Then when the tool 12 is fed by screw 20 80 its point travels a path which describes one face of the desired thread. The other face is cut by the cutting edge of the tool. In the case illustrated, Fig. 1, a 60° thread is represented and consequently, the angle between the line of the lugs 17, 18, which is parallel to the axis of the lathe, and the axis of screw 20 which defines the direction of the feed of the tool is 60°. The base plate 16 is fastened to the slide rest in any 85 suitable manner. The drawing shows means consisting of a bolt hole 36 through the plate, through which a bolt 36' may pass having an under head adapted to engage in the groove 40, like the under head of an 90 ordinary tool post.

The tools are slightly wedge shaped as shown in Fig. 3 to make proper clearance; and the groove is slightly tapering to correspond, being narrower at its bottom. It is 95 therefore adapted to receive tools whose width varies slightly, as may happen in manufacture. At the bottom of this groove is a screw 35. As the tool rests in groove 13 and in clamp 14, 15, it is held firmly; and the pressure of the work upon it when in use pushes it down more firmly into the groove or upon the screw 35, thus holding it rigid in the pedestal 21. The latter is supported at its front end almost immediately under the tool by the aforementioned screw end 26 and is held on the other side by the rigid clamp screw 29 and at the other end by the pivot 22; so that the tool is held firmly and symmetrically supported 110 on a tripod; but is nevertheless free to be fed toward and from the work at its angle of 60° by means of hand wheel 31. If the pressure of the work forces it into groove 13 so tightly that it feeds therein with difficulty, the screw 35 may be raised, thereby taking some of the friction away from the groove sides, because the tool then rests more or wholly upon the screw, the groove sides serving as sidewise guides. The ele- 115 120 125 130

vation of the tool with respect to the work may be adjusted by knurled screw 25 and in case a considerable elevation is desired the pin 22 may be extracted and replaced in a lower hole 22' provided in the pedestal. The friction of the tool in groove 13 enables the hand wheel 31 to be worked with precision.

In operation the cutting face of the tool is 10 the portion marked 12'. When one side of the point of the tool is engaged in cutting, the other side 12'' does not cut ordinarily but merely follows the point in the line in which it is fed. The tool, therefore, operates with an easy and free cutting and its point does not become wedged into the work, as is liable to happen with thread tools of the ordinary type in which the point and the edges on each side of the point are entirely 20 at the same time; nor does it rough the surface of the work. As groove 13 and screw 20 may be positively set at the proper angle by bringing lugs 17, 18 solid against the shoulder of the groove in the cross slide, no 25 gage is needed and no particular care in adjusting the tool to make sure that it is at the right angle. Adjusting screw 25 and clamp 29 to raise or lower the tool does not disturb the pitch or angle of cutting because pivot 30 22 is perpendicular to the feed. Although the tool works ordinarily with only the edge 12' as its cutting edge, for a light shaving to give the final finish to the thread the edge 12'' may be used, the tool being fed for this 35 purpose by a slight motion of the regular cross feed of the lathe which is in the direction of the line B of Fig. 1.

The construction described enables the use of a tool having cutting edges at both 40 ends. Such a tool is illustrated in the drawing, the tool being made symmetrical as to sides and ends and therefore readily reversed. For grinding it is only necessary to hold the tool in a fixture making the 45 proper angle of 30° with the face of the grinder. It is obvious that to cut threads of any different sort or angle suitable variations from the angles mentioned in this description may be made.

50 It will be seen that although the invention is described as primarily applicable to thread cutting, it has features which are applicable to a wider range of uses, and the claims are therefore not restricted to the 55 particular apparatus and uses herein specifically described.

I claim:

1. A thread cutting attachment, comprising a tool rest having means for feeding a 60 tool in a particular direction therewith; a guide on the rest, fixing the line by which the tool may be fed therewith; parts on said rest at points remote from each other, defining a line of abutment adapted to bearing 65 horizontally against an abutment

on a carriage of a suitable machine, such as a lathe, said line of the abutment being at an angle to said line of feed of the tool, and means to fasten the rest in this position, whereby the tool's feeding direction is fixed 70 relative to such carriage; the angle of the thread being determined by said angle between said line of abutment and said line of feed of the tool.

2. The combination of a tool support comprising a base or tool holding pedestal, pivoted theron on a horizontal axis; and tool-feeding means fixed on said pedestal acting in a direction perpendicular to the direction of said pivot axis; there being a vertical 80 screw forming one leg of the pedestal; and a ring with horizontal clamping screw forming another leg; these two with the pivot forming a tripod support for the tool.

3. The combination of a carriage with a shoulder fixed in its angular relation to the axis of the thread which is to be cut; a tool rest adapted to be supported removably on said carriage and having lugs fixed in position on said rest adapted to rest against said shoulder; means to fasten the tool rest thereon; means to hold a tool on said rest, including a groove running in the direction of feed of the tool to the work, said groove having a wall rising laterally beside the tool on the side from which the carriage is fed and adapted to bear against and sustain that side of the tool; said carriage being adapted to be impelled parallel with the axis of the work; whereby the resistance of the work 100 presses the tool normally against said lateral support and presses the tool rest normally against said shoulder of the carriage.

4. The combination of a tool support and feeding means thereon; said support having a 105 groove running in the direction of feed and with open top adapted to receive a tool projecting to variable distances above the top of the groove and to guide such a tool, propelled by said feed; and a screw set in the bottom of said groove and projecting vertically upward therein forming a bottom of variable elevation within the groove on which bottom the tool slides when so propelled.

5. The combination of a tool support and feeding means, comprising a pedestal having ways in the direction of feed; a block to travel in said ways toward and from the work; there being a shoulder arranged on the block; means to clamp the tool against the shoulder; means to feed the block; and a support for the tool between said block and the work.

6. The combination of a tool support and feeding means comprising a pedestal pivoted on a horizontal axis remote from the support, the support being pivoted therewith; the support being pivoted to the pedestal in such a manner that the support may be turned about the horizontal axis to bring the support in line with the work.

ing ways; and a block adapted to travel thereon toward and from the work; means to feed the block; means to fasten a tool to the block; and a support for the tool between said block and the work.

7. The combination of a tool support and tool-feeding means thereon; said support having a groove, running in the direction of feed, adapted to receive and guide a tool 10 propelled by said feed; said groove having an open top and having sides converging slightly downward.

8. The combination of a tool support and tool-feeding means thereon; said support 15 having a groove, running in the direction of feed, adapted to receive and guide a tool propelled by said feed; said groove having an open top and having sides converging slightly downward; and there being in the

bottom of the groove means to support the 20 tool at varying elevations therein.

9. The combination of a tool support and tool feeding means thereon; said feeding means comprising a screw having a journal bearing on said support; the screw shaft 25 having an annular groove and the support having an annular recess registering therewith; an annular key in said groove and recess separable into sections; and means fast on the shaft engaging the support and thereby holding said groove and recess in register.

Signed by me at Boston, Mass., this 1st day of September, 1909.

JOHN F. IVARSON.
